WARP BEAM

Gustaf E. Utter, Worcester, Mass., assignor to
 Crompton & Knowles Loom Works, Worcester,
 Mass., a corporation of Massachusetts

Application January 22, 1949, Serial No. 72,239

9 Claims. (Cl. 242—124)

1

This invention relates to improvements in warp beams and it is the general object of the invention to provide a simple form of adjustable warp engaging flange or head which can be rigidly clamped in adjusted position on the barrel of the beam.

The warp threads used in looms are customarily wound on a beam mounted for rotation at the back of the loom. The width of the warp varies with the width of the cloth being woven in the loom and provision is usually made for adjusting the width of the warp space of the beam by means of flanges or heads which can be moved along the beam barrel to different positions. When beams of large diameter are employed there is considerable end pressure tending to cause either slippage or change of position of the flange heads on the beam barrel as the warp accumulates during the winding operation.

Heretofore attempts have been made to secure the beam head securely to the beam barrel, usually by some means acting radially of the barrel and having little or no effect in moving the head lengthwise of the barrel. It is an important object of the present invention to provide a warp head or flange with means, such as blocks or the like, which can not only be clamped tightly against the screw threads on the barrel but also effect movement of the screw threads on the head lengthwise of the barrel into tight holding relation with the threads thereon. This effects, as it were, a preloading of the head so that it will not slip as the warp is wound on the barrel. The preloading has the effect of moving the head to its extreme position in the direction in which the warp will try to move it prior to the start of the winding operation.

It is a further object of the invention to pivot locking blocks or the like to the warp head at points spaced outwardly from the barrel so as to give additional support to the head beyond that which it derives directly from the barrel. The effect of this supporting can be enhanced by making the blocks oblique with respect to the barrel.

With these and other objects in view which will appear as the description proceeds, the invention resides in the combination and arrangement of parts hereinafter described and set forth.

In the accompanying drawings, wherein a convenient embodiment of the invention is set forth,

2

Fig. 1 is a front elevation of a warp beam made according to the present invention.

Fig. 2 is a vertical section on line 2—2, Fig. 1.
 Fig. 3 is an enlarged vertical section on line

5 3—3, Fig. 2,

Fig. 4 is an enlarged section on line 4—4, Fig. 3.
 Fig. 5 is a perspective view of one of the clamping blocks.

Figs. 6 and 7 are diagrammatic views showing the manner in which the warp head is preloaded, and

Fig. 8 indicates the manner in which the screw threads may be cut on the inner ends of the clamping blocks.

10 Referring particularly to Fig. 1, the warp beam comprises a barrel 10 which is preferably a metal tube formed at each end thereof with external screw threads 11. Supporting gudgeons 12 project beyond the ends of the barrel and one end 15 of the latter may be provided with a friction drum 13 if desired to accommodate a letoff strap or the like when the beam is in a loom.

Screw threaded on the barrel are warp engaging heads H which are adjustable along the 20 screws 11 so that the warp space between the heads may be varied to accommodate warps of different widths. Since these heads H are alike a detailed description will be given of only one of them.

25 Referring more particularly to Figs. 2 to 5, the head H has a flat web 20 having a smooth surface 21 for engagement with the warp threads. The web 20 is formed integrally with a hub 22 which is connected to the web by several reinforcing ribs. As shown in Fig. 2 three ribs 23 30 extend from the hub to the outer rim 24 of the web. The hub is provided with internal screw threads 25 which fit the screw threads 11 on barrel 10.

35 In addition to the reinforcing ribs 23 there are other shorter ribs 26 arranged in pairs and leading inwardly from the rim. Each pair of these shorter ribs leads to and is integral with a walled structure designated generally at 27 and including side walls 28 and 29 jointed by a cross on transverse wall 30. These walls define between them a cavity or recess 31 having a floor 32. As shown in Fig. 2 three of these recesses and walled structures are set forth, but any other number 40 can be used if desired.

45 Each wall structure 27 is provided with a pivot pin 35 which passes through the walls 28 and 29 and across the recess 31 and spaced from floor 32. Pivoted on each pin is a clamping block or 50 bar 36 the inner end of which adjacent to the

barrel is provided with screw threads 37 which fit the screw threads 11. A draw screw 38 extending generally in direction of the length of the barrel passes through a clear hole 39 in the block and is tapped into a screw threaded hole 40 in the head H which preferably does not extend to surface 21, see Fig. 3.

The clamping block 36 may be made either of steel, cast iron, or other suitable metal. If made of cast iron, or the same material of which the head H is made, the screw threads 37 can be cut by the same operation by which the screw threads 25 are cut on the hub 22. Prior to this operation a washer 41 or the like will be interposed between the surface 42 of the block and the floor 32 of the recess 31 to keep the block spaced from the floor. The draw bolt is then inserted through hole 39 and the washer and threaded into tapped hole 40 and then tightened. The inner end of the block is thus held in rigid position with respect to the head H and the same tool 43 which cuts the screw threads 25 will also cut the threads 37, see Fig. 8. After the threads are cut the draw bolt can be removed and the washer taken out of the recess 31. The draw bolt is then re-inserted into the tapped hole 40.

If the blocks are made of some material which will not cut readily in the set-up shown in Fig. 8 they can be prepared by a separate operation.

After the blocks have been assembled on their pins the latter can be held against endwise movement of the walls 28 and 29, as by retaining pins 45. The draw bolts will be left loose enough to permit the screw threads 37 to find their place on the threads 11 when the head is threaded onto the barrel. The head will then be moved along the screw 11 to the desired position, after which the draw screws will be tightened to cause the blocks to be firmly clamped against the barrel.

In the commercial production of warp beams it is usual experience that the screw threads on the barrel will not have a perfect fit with the screw threads 25 or 37, and there will necessarily be some looseness of fit in order to permit easy turning of the head H. When the head is in its desired position the relation of its threads 25 with respect to the threads 37 and the thread 11 may be as shown in Fig. 6. If the head were to be left in this position the accumulating thickness of warp threads during the winding operation would exert an end pressure which would move the flange to the right, Fig. 6. By tightening the draw screws prior to winding, however, the clamping blocks have the effect of moving the head to the right from the position shown in Fig. 6 to that shown in Fig. 7, or in the direction in which the warp will try to move the head on the barrel. When the pressure of the accumulating warp threads is thereafter exerted against the surface 21 the screw threads 25 will not be able to move any farther to the right because of the preloading of the head resulting from tightening of the draw screws 38. Since the latter engage only a small part of the periphery of the threads 11 they can be completely seated in the screw threads 11 as shown at the right of Fig. 7, thereby establishing a very firm grip on the beam which will resist any endwise motion toward the adjacent end of the barrel.

A significant feature of the invention is shown in Fig. 3 where it will be seen that the block 36 is oblique to or inclined with respect to the barrel 10. The threads 37 of the block lie largely if not entirely to one side of a radius of the barrel

passing through the pivot pin 35. As a result of this relationship the block has an action somewhat similar to that of a toggle when the draw screw is tightened and exerts considerable force 5 on the threads 11 and also braces those parts of the web 20 adjacent to the pins 35 and spaced from the barrel.

From the foregoing it will be seen that the invention sets forth simple means by which forces 10 can be exerted on the head or flange lengthwise of the barrel to preload the head. As shown herein the means for accomplishing this result include clamping blocks which are pivoted on the warp head and are movable by draw screws in 15 the direction of the axis of the barrel to take up slackness between the screw threads 11 on the beam barrel and screw threads 25 on the hub of the head, see Figs. 6 and 7. Because of the preloading of the head it will not slip as warp 20 threads accumulate on the barrel during the winding operation. It will also be seen that the blocks are slightly oblique with respect to the barrel, although this is not an essential relation for all uses of the invention. The blocks 25 are pivoted so they move in a plane which preferably passes through the axis of the barrel 10, or hub 22. The pivot pins 35 are transverse of the barrel and spaced therefrom to support the web 20 at points located some distance out from the 30 surface of the barrel. Also, because of the fact that there is normally a space between the block 36 and the floor 32 of the pocket 31 it is possible by the use of a washer, shim, or similar device to hold the blocks firmly to the head so that the 35 screw threads 25 and 37 may be cut in a single operation.

Having thus described the invention it will be seen that changes and modifications of the foregoing specific disclosure may be made without departing from the spirit and scope of the invention.

What is claimed as new is:

1. In a warp beam having a barrel with external screw threads thereon, a warp head having a hub provided with internal screw threads threaded onto the screw threads of the barrel, a clamping block pivoted on the warp head and movable angularly relatively to the warp head in the direction of the axis of the hub, screw threads 45 on said block meshing with the screw threads of the barrel, and means interconnecting the block and warp head by which the latter can be moved lengthwise of the barrel to take up slack between the screw threads of the hub and barrel to preload the warp head.

2. In a warp beam having a barrel with external screw threads thereon, a warp head having a warp thread engaging surface on one side thereof and having a hub provided with internal screw threads threaded onto the screw threads of the barrel, a clamping block pivoted on the warp head on the other side thereof at a point spaced outwardly from the barrel and movable angularly relatively to the warp head in the direction of the length of the hub, screw threads on the block engaging the screw threads of the barrel, and means interconnecting the block and warp head by which the latter can be moved along the barrel to take up slack between the screw threads of the hub and barrel to preload the warp head.

3. In a warp beam having a barrel with external screw threads thereon, a warp head having a hub provided with internal screw threads threaded onto the screw threads of the barrel, a 75 clamping block disposed obliquely with respect to

the axis of the hub and pivoted on the warp head and movable angularly relatively to the latter in the direction of the axis of the hub, screw threads on said block meshing with the screw threads of the barrel, and means interconnecting the block and warp head by which the latter can be moved along the barrel to take up slack between the screw threads of the hub and barrel to preload the warp head.

4. In a warp beam having a barrel with external screw threads thereon, a head having a hub provided with internal screw threads threaded onto the screw threads of the barrel, means on the warp head constituting a pivot the axis of which is spaced from and transverse of the hub, a clamping block on said pivot having screw threads meshing with the screw threads on the barrel, and means interconnecting the block and warp head to effect movement of the warp head along the barrel while the screw threads of the block are meshed with the screw threads of the barrel.

5. In a warp beam having a barrel with external screw threads thereon, a warp head having a warp thread engaging surface on one side thereof and having also a hub provided with internal screw threads threaded onto the screw threads of the barrel, a pivot pin on the other side of the warp head transverse of the axis of the hub, a clamping block pivoted on said pin and movable thereon angularly relatively to the warp head in the direction of the axis of the hub, said block having an end thereof engaging the barrel and held against movement lengthwise of the barrel, and means interconnecting the block and warp head by which the latter can be moved toward said end of the block to take up slack between the screw threads of the hub and barrel to preload the warp head.

6. In a warp beam having a barrel with external screw threads thereon, a warp head having a warp thread engaging surface on one side thereof and having also a hub provided with internal screw threads threaded onto the screw threads of the barrel, a pair of walls on the other side of the warp head, a pivot pin supported by said walls spaced from the hub and extending transverse of the axis thereof, a clamping block pivoted at one end thereof on said pin for angular movement toward and from the head in a plane which passes through the axis of the hub, screw threads on the other end of the block meshing with the screw threads on the barrel, and a draw screw passing through the block and threaded into the warp head and extending generally in the direction of the length of the hub and effective when tightened to cause movement of the hub toward said other end of the block to take up slack between the screw threads of the hub and barrel to preload the warp head.

7. In a warp beam having a barrel with external screw threads thereon, a warp head having a warp thread engaging surface on one side thereof and having also a hub provided with internal

screw threads threaded onto the screw threads of the barrel, a pivot pin mounted on the other side of the warp head spaced from said hub, a clamping block pivoted at one end thereof on said pin for angular movement relatively to the warp head, said pin being so disposed that the block is movable angularly thereon in the direction of the length of the hub, screw threads on the other end of said block engaging the screw threads of the barrel and located partly at least on that side at a radius of the hub passing through the pivot pin opposite to said warp engaging surface, and a draw screw passing through the block and tapped into the warp head and effective when tightened to move the hub in a direction from said warp engaging surface toward the screw threads on the block to take up slack between the screw threads of the hub and the barrel to preload the warp head.

8. In a warp beam having a barrel with external screw threads thereon, a warp head having a hub provided with internal screw threads threaded onto the screw threads of the barrel, a walled structure on the warp head having parallel walls between which extends a floor, a pivot pin supported by said walls, a clamp block pivoted on said pin between said walls and normally spaced from said floor, screw threads on said block engaging the screw threads of the barrel, and a draw screw passing through the block and through said floor and tapped into the warp head and effective when tightened to draw the screw threads of the hub longitudinally of the barrel in a direction toward the screw threads of the block to take up slackness between the screw threads of the hub and the barrel to preload the warp head.

9. In a warp beam having a barrel with external screw threads thereon, a warp head having a warp thread engaging surface on one side thereof and having also a hub provided with internal screw threads threaded onto the screw threads of the barrel, a walled structure on the warp head including two spaced walls between which a floor on the warp head extends, a pivot pin supported by said walls extending transversely of the hub, a clamping block pivoted on said pin for angular movement relatively to the warp head in a plane passing through the axis of the hub, said clamping block being normally spaced from said floor, screw threads on said clamping block engaging the screw threads of the barrel, and a draw screw passing through said block and floor and tapped into said warp head and effective when tightened to effect relative movement of the hub and barrel to take up slack between the screw threads of the hub and barrel, said clamping block being oblique with respect to the axis of the hub and having part at least of the screw threads thereof disposed on that side of a radius of the hub passing through said pivot pin opposite to said warp engaging surface.
